United States Patent Office.

CHARLES PINDER AND DON C. ROBINSON, OF LOWELL, MASSACHUSETTS.

Letters Patent No. 70,856, dated October 29, 1867.

IMPROVED CAR-AXLE BOX.

The Schedule referred to in these Letters Patent and making part of the same.

TO ALL WHOM IT MAY CONCERN:

Be it known that we, CHARLES PINDER and DON C. ROBINSON, both of Lowell, in the county of Middlesex, and State of Massachusetts, have invented new and useful Improvements in Car-Boxes; and we do hereby declare that the following is a full and exact description thereof, reference being had to the accompanying drawings, and to the letters of reference marked thereon.

The nature of our invention consists in providing a car-box with four or more bearings, the object of which is to change the worn-out bearing, with the least inconvenience and loss of time, for a new bearing, without replacing a new box entire. It also relates to the chamber, formed through the centre of the box, which chamber serves to keep the working bearing cool, and also is an aid in changing the box.

To enable others skilled in the art to make and use our invention, we will proceed to describe its construction and operation.

Figure 1 represents a plan of our improved car-box with four bearings.

Figure 2 represents a section through A and B of fig. 1.

a represents the box, *b* the cooling-chamber, *c c c c* the Babbitt linings, and *d d d d* the bearings.

Much inconvenience, expense, delays, and danger to trains attend the usual boxes now used for car-axles. First, the ordinary box, having but one bearing, when this is worn out, melted, or destroyed by heat, caused by friction, and not being properly lubricated, the box becomes worthless, useless, and unserviceable, and valuable only to be remelted. Besides this, having but one bearing, the box suddenly giving out when the train is at a long distance from a repair-shop, the inconvenience and delay are often very great. And, further, it is continually liable to heat when the train is running, for the want of a collar near its bearing.

In our improved car-box these several serious difficulties, to a great extent, are remedied. Each bearing, *d d*, in our car-box is equivalent and equal to an entire new box of the common ordinary kind now in use.

We construct our improved box *a* of one piece of metal, of a suitable length, of any size, form, or shape. On its outside surface we form four or more bearings, *d d d d*, as may be desired. In these bearings *d d d d* chambers are formed, which we fill or line with Babbitt *c c c c*. We also form a chamber, *b*, through the entire length of the box *a*, as large as can be made without weakening or endangering the breaking of the box *a* in its centre or thinnest part. This chamber *b* acts as a cooler to the working bearing, as the air is constantly changing therein. And, further, this chamber *b* is useful and convenient for the engineer when short of time and a whole train stopped, in assisting in removing, with a proper instrument, the box *a* from the housing, and changing an old bearing for a fresh and new one, and replacing the same.

The box *a*, being thus prepared, the engineer places the same in the housing over the axle-journal, its opposite side resting on a suitable bolster, or on its outside edges. The bearing *d* being in working contact with the running-journal of the axle, the duration of its wear is longer than the common box, owing to the constant supply of cool air around the box *a* and in the chamber *b*.

Thus it will be apparent, our box *a*, having four bearings *d d d d*, gives four times the wear of the ordinary box, is easier changed when required, less danger to a train when running, as there is less danger in melting the Babbitt in the box, and, on the whole, cheaper, safer, and more durable.

What we claim as our invention, and desire to secure by Letters Patent, is—

A car-axle box, *a*, having bearing-surfaces *d d d d*, each being ready provided with Babbitt or equivalent soft metal *c*, and arranged to be in turn placed in position for use, substantially as described, and for the purpose set forth.

We also claim the cooling-chamber *b*, in combination with the box *a*, for the purposes substantially as herein described.
